ALLAN O. CARPENTER, OF CORNING, NEW YORK, ASSIGNOR TO INGERSOLL-RAND COMPANY, OF JERSEY CITY, NEW JERSEY, A CORPORATION OF NEW JERSEY.

COOLING MEANS FOR COMPRESSORS AND PUMPS.

1,368,238.

Specification of Letters Patent. Patented Feb. 15, 1921.

Application filed March 22, 1920. Serial No. 367,969.

To all whom it may concern:

Be it known that I, ALLAN O. CARPENTER, a citizen of the United States, residing at Corning, in the county of Steuben and State 5 of New York, have invented a certain new and useful Improvement in Cooling Means for Compressors and Pumps, of which the following is a specification.

This invention relates to air or gas compressors or vacuum pumps, and has to do 10 particularly with means for cooling the cylinders and other parts thereof by the circulation of a cooling medium, preferably air.

It has been customary to overcome the effects of increased temperatures produced in 15 the operation of compressors and pumps, for instance, by cooling the cylinders through the utilization of water or other liquid circulating through a jacket surrounding the cylinder. Some machines of this kind, such as 20 small types of single acting vacuum pumps, have been constructed so that they are cooled by atmospheric air, the water jacket being used for this purpose, and in other air cooled 25 machines unsightly ribs have been formed on the cylinders. Such air cooling is entirely inadequate and for that reason cannot be used for large types of engines, and, indeed, it is quite inefficient when used in small ones.

The object of the present invention is to 30 eliminate the unsatisfactory features of prior constructions and to efficiently and economically cool the cylinders of vacuum pumps, compressors and similar apparatus 35 by means of a thorough circulation of air around the cylinder and other parts of the machine, whereby air-cooling may be generally resorted to for machines of the types set forth, even in large sizes.

This object, as well as others which will 40 later appear, is accomplished by the device a practical embodiment of which is described in the following specification and illustrated in the accompanying drawing, forming a 45 part hereof, in which—

Figure 1 represents a vertical sectional view through the center of a vacuum pump embodying the invention; and

Fig. 2, a sectional view on the line 2—2 50 of Fig. 1.

The vacuum pump comprises a cylinder A in which reciprocates a piston B actuated by a connecting rod C secured to a wrist pin D trunnioned in the piston B. The connect-

ing rod C is attached to a crank E secured 55 to a shaft F which is rotated in bearings G—G through a belt wheel or pulley H connected with an outside source of power (not shown). Surrounding the cylinder A is an outer casing I. The connecting rod, crank, 60 bearings, and other parts constituting the operating means for the piston are inclosed by the lower end J of this casing I, which lower end has a diameter slightly greater than the upper portion I. An open jacket 65 or compartment L is thus provided surrounding the piston operating means and extending upwardly between the outer wall of the cylinder A and inner walls of the casing I, as shown at K, whereby a continuous 70 chamber K—L is provided within the casing enveloping the cylinder and the piston operating means. This continuous chamber is utilized to cool the cylinder and other parts in the manner presently to be described.

It will be seen that this chamber does not extend entirely around the cylinder (see Fig. 2) except at the upper end where an annular chamber P, forming a part of the main cooling chamber K is formed, this chamber P being provided with a plurality of constantly open ports Q leading to atmosphere. In the ends of the crank case within the outer casing J are cast walls or ribs R the 85 upper portions of which serve to support the shaft F and bearings G, these walls forming, in effect, an inclosing casing for the moving parts of the piston operating mechanism. Chambers O—O are thus provided between these walls R and the outer casing J communicating by means of ports S, with the chamber L, and hence, the chambers K and P. Diagonally opposite constantly open ports T—T in the casing J, one 90 adjacent to each end of the shaft F, communicate with atmosphere. This construction serves to prevent the entrance of foreign matter into the crank case, as well as to facilitate the carrying out of the purpose of 95 this invention.

From the above it will be seen that a continuous chamber O—L—K—P, communicating with atmosphere at its upper and lower ends by means of the ports Q and T respectively, constituting a common cooling means, is provided. Oil or other liquid is usually present in the crank case, rising to a point

above the ports S. The air entering the crank case through the ports T serves to cool this liquid.

The operation of the present apparatus 5 will be clear from the above description. Thorough circulation of the air is effected by the reciprocation of the piston and movement of the crank parts, air being alternately drawn in and expelled through the 10 ports Q by the pulsatory action taking place within the casing J, so that the well understood "breathing" effect is obtained. It will thus be seen that a continuous uninterrupted flow of cool air around the cylinder and 15 other parts will occur as long as the machine is in operation. A very thorough cooling of the parts results, which contributes materially to the all-around efficiency of the machine.

20 It is to be understood that the present showing and description disclose only one specific embodiment of the present invention and that other forms and modifications are included within the spirit and scope of the 25 same, as expressed in the appended claims, the essence of the invention comprising the provision of a continuous common chamber around the cylinder and moving parts within the crank case for cooling purposes.

30 Having thus described my invention, what I claim and desire to secure by Letters Patent is:

1. A vacuum pump or compressor, comprising a casing, a cylinder and crank case 35 within said casing, a common cooling chamber between said casing and cylinder and between said casing and crank case, and means for maintaining circulation of a cooling medium through said chamber.

40 2. A vacuum pump or compressor comprising a casing, a cylinder and crank case within said casing, a piston within said cylinder, operating means for said piston, a common cooling chamber between said casing and cylinder and between said casing and crank case, and means whereby the piston and its operating parts serve to maintain circulation of a cooling medium through said chamber.

45 3. A vacuum pump or compressor comprising a casing, a cylinder and crank case within said casing, a common cooling chamber between said casing and cylinder and between said casing and crank case, and means 55 for admitting a cooling medium to said chamber and discharging it from said chamber adjacent to said cylinder.

50 4. A vacuum pump or compressor comprising a casing, a cylinder and crank case 60 within said casing, a piston within said cylinder, operating means for said piston, a common cooling chamber between said casing and cylinder and between said casing and crank case, and constantly open ports 65 for admitting a cooling medium to said

chamber and discharging it from said chamber adjacent to said cylinder through the agency of the piston and its operating means.

5. A vacuum pump or compressor comprising a casing, a cylinder and crank case 70 within said casing, a common continuous cooling chamber extending from the surface of said cylinder to said crank case, ports in said outer casing for admitting a cooling medium to said crank case and for discharging said cooling medium, and means for maintaining a continuous circulation of the cooling medium through said chamber.

6. A vacuum pump or compressor comprising an outer casing, a cylinder and crank 80 case within said casing, a piston, operating means for said piston, a common continuous cooling chamber extending from the surface of said cylinder to said crank case, ports in said outer casing for admitting a 85 cooling medium to and discharging said cooling medium from said crank case and means whereby the piston and piston operating means serve to maintain a continuous circulation of the cooling medium through 90 said chamber.

7. A vacuum pump or compressor comprising an outer casing, a cylinder, a piston in said cylinder, operating means for said piston, a common cooling chamber within 95 said casing surrounding the cylinder and piston operating means, and means whereby the admission and expulsion of cooling medium is effected by movement of the piston operating means.

8. A vacuum pump or compressor comprising an outer casing, a cylinder, a piston in said cylinder, operating means for said piston, a common cooling chamber within said casing surrounding said cylinder and 105 operating means, an annular chamber around said cylinder forming a part of the common cooling chamber and ports in said casing for admitting a cooling medium to said chamber and for discharging the cooling medium therefrom to maintain a continuous circulation of said cooling medium 110 through said chamber.

9. A vacuum pump or compressor comprising an outer casing, a cylinder, a piston 115 in said cylinder, operating means for said piston, a common cooling chamber within said casing surrounding said cylinder and operating means, an annular chamber around said cylinder forming a part of the common cooling chamber and ports in said casing for admitting a cooling medium to said chamber and for discharging the cooling medium therefrom, the moving parts of said structure constituting pulsatory means for 120 maintaining a continuous circulation of said cooling medium through said chamber.

In testimony whereof I have hereunto set my hand.

ALLAN O. CARPENTER.
